(57) **CLAIM**

I claim the ornamental design for the slicing tool blade tray,
as shown and described.

DESCRIPTION

FIG. 1 is a front view of the slicing tool blade tray;

FIG. 2 is a top view of the slicing tool blade tray;

FIG. 3 is a right side view of the slicing tool blade tray;

FIG. 4 is a bottom view of the slicing tool blade tray;

FIG. 5 is a back view of the slicing tool blade tray;

FIG. 6 is a left side view of the slicing tool blade tray;

FIG. 7 is a perspective view of the slicing tool blade tray;

and,

FIG. 8 is a perspective view of the slicing tool blade tray,
configured within a slicing tool reservoir having a lid in an
open position.

The blades in FIGS. 1, 5, 7, and 8 are shown in phantom,
with the particular arrangement of the blades forming no
part of the invention. The slicing tool, including its lid and
reservoir, are shown in phantom in FIG. 8, and forms no part
of the invention. A vertical element, visible in phantom in
FIGS. 1, 7, and 8, is shown in phantom and forms no part of
the invention.
